UNITED STATES PATENT OFFICE

142,384

DESIGN FOR A FOUNTAIN PEN

Lynn P. Martin, Fort Madison, Iowa

Application November 17, 1944, Serial No. 116,371

Term of patent 14 years

(Cl. D74—17)

To all whom it may concern:

Be it known that I, Lynn P. Martin, a citizen of the United States, residing at Fort Madison, in the county of Lee and State of Iowa, have invented a new, original, and ornamental Design for a Fountain Pen, of which the following is a specification, reference being had to the accompanying drawing, forming a part thereof.

Figure 1 is a side elevational view of a fountain pen embodying my new design; and

Fig. 2 is a front elevational view of Figure 1.

The dominant feature of my design resides in the writing point end of the fountain pen shown in full lines.

I claim:

The ornamental design for a fountain pen, substantially as shown and described.

LYNN P. MARTIN.
